APPARATUS FOR SIMULTANEOUSLY POLISHING BOTH FACES OF A TRAVELLING STRIP OF GLASS

Granville Hugh Baillie, London, England, assignor to Pilkington Brothers Limited, Liverpool, England, a British company

Application April 9, 1946, Serial No. 660,714
In Great Britain September 13, 1944

2 Claims. (Cl. 51—195)

1

This invention relates to apparatus for simultaneously polishing both faces of a travelling strip of glass.

Such form of apparatus commonly comprises polishing tools adapted to operate on the under-surface of the glass strip, whilst at the same time they serve to support the strip, each such tool including a plurality of polishing pads each adapted to turn on a substantially vertical axis, the tool being mounted on a frame which is adapted to rotate so as to bring each pad to an edge of the glass.

The tool may either be supported on a single frame with central driven shaft or may be supported on a plurality of sub-frames in turn supported on a main frame with central driven shaft, each sub-frame (if used) being free to rotate on its support on the main frame. Each tool is provided with means of vertical adjustment, whereby the strip of glass supported by the plurality of tools can be kept free of bends in passing through the apparatus.

Polishing is effected by the rubbing of the pads over the glass, while rouge and water is supplied either to the pads or to the glass. After a certain time of operation, rouge becomes caked on the pads to form a hard layer, in which foreign matter such as glass splinters may be embedded, and the polishing action is then impaired. The pads then have to be cleaned by removing the hard layer and, to effect this, access must be obtained to the operative surface of the pads. Further, the pad coverings gradually wear and may become damaged and then the coverings must be removed and replaced.

If a polishing tool operating on the under-surface of a strip of glass be lowered so as to give access to the surfaces of the pads, there is risk of the travelling glass, which is then left unsupported over the tool, breaking. Also, if one or some of the pads have their covering replaced, the pads with new coverings are not accurately in the same plane as the remaining pads with partially worn coverings. This has the result of imposing bending stresses on the glass which may be sufficient to break the glass.

A main object of the present invention is to provide in apparatus for simultaneously polishing both faces of a travelling strip of glass, means whereby a pad operating on the under-surface of the glass can be rapidly moved away so that the pad can either be replaced or its surface scraped or cleaned, and its surface adjusted into the plane in which the other pads mutually support the glass.

2

In accordance with the present invention apparatus for polishing the under surface of a horizontal travelling strip of glass as it comes from the lehr comprises polishing tools which support the strip during polishing, each tool comprising a frame adapted to turn on a vertical axis, and a plurality of polishing pads supported on said frame, each pad being mounted to turn on a vertical axis, characterised by a supporting member for each pad pivoted to the frame about a horizontal pivot distant from the axis of the pad by at least the radius of the pad, a locking device individual to each pad mounted on the pad supporting member, said locking device when in operative position rigidly holding the respective pad in polishing position on the pad supporting member, and in inoperative position releasing the respective pad from said pad supporting member, whereby the pad is freed to fall about its horizontal pivot away from the glass and to give access to its operative surface, and means individual to each pad for adjusting the pad along its vertical axis in the pad supporting member.

25 In the accompanying drawings is shown by way of example one embodiment of the invention as applied to apparatus for polishing glass including co-axial polishing tools operating simultaneously on both surfaces of the glass.

30 In the drawings:

Figure 1 is a plan view of a lower polishing tool with three pads, partly broken away, and without the glass strip above it;

Figure 2 is a vertical section on the line A—A' of Figure 1; and

Figure 3 is an elevation partly in section on the line A—B of Figure 1.

The driving shaft 1 of the polishing tool carries a frame 2, which supports three polishing pads 3 with felt coverings 4, operating on the under-surface of a travelling strip of glass 5, which is driven slowly by driving rollers (not shown) in known manner between co-axial polishing tools, of which the lower tool only is shown.

45 Each pad is supported by a pin 6 which is free to rotate in a sleeve 7, which is adapted to slide vertically in the cup-shaped end 8 of an arm 9 pivoted at 10 in a fork of the frame. The arm 9 has a depending lug 11 which, when the pad is in operative position as in Figures 1 and 2, is held in this position by two screws 12 passing through the fork of the frame and engaging recesses 13 in the lug. On withdrawing the screws 12 from the recesses 13, the arm 9 with the pad, 50 is free to turn about its pivot 10 into the posi-

tion shown in Figure 3, in which its operative surface 4 is exposed to permit the felt covering to be changed, or the surface cleaned by scraping.

It is to be noted that the pivot 10 of the member 9 is vertically below the extreme edge of the pad and that, consequently, no part of the pad has an upward motion as the pad moves from the position of Figure 2 to that of Figure 3. The pivot 10 may be further from the centre line of the pad than the extreme edge of pad, but not closer to it.

The sleeve 7 in which the pad is carried is supported vertically in the cup-shaped end 8 of the member 9 by means of the screw 14 in the bottom of the end 8. By turning the screw 14, the height of the pad is adjusted, and thereby the operative surface of the pad may be brought into the plane coincident with the plane of the under surface of the strip of glass 5.

It is to be noted that, when a pad is moved from its operative position to the position of Figure 3, to give access to its operative surface, and is returned to its operative position, its operative surface reverts to the original position to which it had been adjusted by the screw 14.

When it is desired to replace a felt the pin 6 can be lowered to facilitate access to the pad as in any case the pin would have to be lowered to accommodate the new and thicker felt.

By means of the construction above described, any pad may be withdrawn from the glass to give access to its surface, leaving the other pads in operative position supporting the glass and, further, each pad is adjustable in vertical height, and this adjustment is not disturbed by the movement of the pad giving access to its surface.

In the description just given the pads are described as being mounted on vertical axes. The axes may, however, be slightly tilted from the vertical and the term "vertical" used herein is intended to include either a truly vertical or substantially vertical axis.

1. claim:

1. Apparatus for polishing the undersurface of a horizontal travelling strip of glass as it comes

from the lehr comprising polishing tools which support the strip during polishing, each tool comprising a frame adapted to turn on a vertical axis, and a plurality of polishing pads supported on said frame, each pad being axially slidably mounted and journaled to turn on a vertical axis, characterised by a supporting member for each pad pivoted to the frame about a horizontal pivot distant from the axis of the pad by at least the radius of the pad, an independent locking device for each pad mounted on the pad supporting member, each locking device when in operative position rigidly holding its pad in polishing position on the pad supporting member, and in inoperative position releasing its pad from said pad supporting member, whereby the pad is freed to fall about its horizontal pivot away from the glass and to give access to its operative surface, and individual adjusting means for each pad for sliding the pad along its vertical axis in the pad supporting member.

2. Apparatus as recited in claim 1 wherein said individual adjusting means for each polishing pad comprises a sleeve mounted for vertical movement in said supporting member, a pin depending from the pad and extending into said sleeve, and a sleeve adjusting member mounted in said supporting member below said sleeve and turnable to vary the vertical position of said sleeve.
